DESIGN FOR A PORTABLE MIRROR- STEREOSCOPE ASSEMBLY

Harrison C. Ryker, Oakland, Calif.

Application June 28, 1940, Serial No. 93,300

Term of patent 14 years

To all whom it may concern:

Be it known that I, Harrison C. Ryker, a citizen of the United States and a resident of the city of Oakland, county of Alameda, State of California, have invented a new, original, and ornamental Design for a Portable Mirror-Stereoscope Assembly, of which the following is a specification, reference being had to the accompanying drawing, forming part thereof.

Figure 1 is a side elevational view of a portable

mirror-stereoscope assembly, showing my new design.

Figure 2 is a plan view of the assembly as shown in Figure 1.

Figure 3 is an end view.

I claim:

The ornamental design for a portable mirror-stereoscope assembly, substantially as shown.

HARRISON C. RYKER.
